RETAINER MOLDING FOR FLOOR
COVERINGS

Samuel P. June, Willoughby, Ohio

Application September 13, 1949, Serial No. 115,382

2 Claims. (Cl. 16—7)

1

This invention relates to means for securing the edge of a rug and the like against movement out of its position of normal lay and for preventing movement of a floor covering from its floor covering position.

Floor coverings particularly throw rugs are dangerous sources of accidents when allowed to remain on a smooth walking surface especially near a doorway or at the foot or head of a stairs. Floor coverings in these places have the tendency to move out from under a person stepping thereon when that person steps thereon with a strong forward movement. These rugs as well as normal size room rugs have a tendency for their edges to be kicked up out of normal rug laying position tending to cause a person moving onto the rug to trip. Rug coverings behaving in this manner are a constant danger to persons walking thereon.

These dangers may be eliminated from floor coverings behaving in this manner by applying to these coverings the device of the present invention.

It is an object of this invention to provide a rug guard or similar device for securing the edge of a floor covering against movement out of the plane of the rug and thereby insure normal walking conditions relative to the lay of the rug.

Another object is to provide a rug guard having a resilient and tapered rug gripping lip adapted to move into biasing position with the edge of a rug and hold it against movement away from the guard.

A further object is to provide a rug guard having securing means concealed against exposure by the gripping lip.

Still another object is to provide a rug guard having slotted means for receiving the guard securing means in concealed position.

A still further object is to provide a rug guard having a body portion provided with a deformable member responsive to deformation on movement of the securing means into holding position thereby permitting the rug gripping lip to move into rug holding position.

With these objects in view and other objects which will appear as the description proceeds, the invention consists in providing a facile, efficient and economical rug guard having various parts best illustrated in the accompanying drawings in which:

Fig. 1 is an end view showing a preferred form of rug guard positioned adjacent the edge of a rug.

Fig. 2 is an end view showing the rug guard of Fig. 1 in operating position.

Fig. 3 is an end view of a rug guard having deformable means and being positioned adjacent the edge of a rug.

2

Fig. 4 is an end view showing the rug guard of Fig. 3 in operating position.

Figs. 5 and 7 are end views of rug guards showing modified designs of the body portion of the guard.

Fig. 6 is a cross section of a rug guard showing a further modified design of the body portion of the guard.

Fig. 8 is an end view of a rug guard provided with non-skid ribs and an insert for equalizing the pressure exerted by the securing means.

Fig. 9 is an end view of a rug guard provided with a modified form of deformable means.

Fig. 10 is a cross sectional view of a rug guard provided with a concave base.

Fig. 11 is an end view showing a rug guard provided with slotted means for receiving a securing means in concealed position.

The rug guard shown in Figs. 1 and 2 comprise 20 a main body portion 1 having a flat floor engaging base 2, a tapered floor engaging tail 3, a securing means receiving portion 4 and a tapered rug gripping lip 5. The lip 5 is hinged to the body portion 1 in such a manner that the lip may 25 be moved upwardly far enough to expose portion 4 and permit the positioning of a securing means as a nail 6 therein until it is received into the rug supporting member or floor 7, and then be moved downwardly to cover the head of the nail 6 and at the same time engage the edge of the rug 8 and secure it against movement away from the guard.

The movability of the lip 5 is due to the resilient nature of the material from which the 35 guard is made. Any resilient rubbery material including natural and synthetic rubbers such as Buna S, or Buna N may be used as well as any synthetic elastic resin and plasticized resins including the acrylates, polyamides and the like. 40 The guard is formed by extruding the material through a die of the proper design.

Figs. 3 and 4 show a rug guard 9 comprising a 45 tapered floor engaging tail 10, a floor engaging foot portion 11 joined to the tail 10 through the arched member 12 and a tapered rug gripping lip 13. The foot portion 11 is provided with a recessed portion 14 through which the nail 15 is driven downwardly through the foot 11 into the floor 7. When the nail 15 is driven into the floor 50 7 and the head of the nail 15 is received in the slot 14 the foot portion 11 and tail 10 tend to move away from each other through the flexing action of the arch member 12 thereby causing the lip 13 to move into positive holding engagement with the rug 8 as shown in Fig. 4.

Figs. 5, 6 and 7 each show a modification of the rug guard shown in Fig. 3. These modifications indicate methods of permitting the down-

ward movement of the guard by a securing means driven into the guard in the same manner described for Figs. 3 and 4. The guard shown in Fig. 5 comprises a curved body portion 16 terminating at one end in a tapered tail portion 17 and at the other end in a downwardly curved and tapered rug engaging lip 18 with resilient supporting ribs 19 extending downwardly from the body portion 16. A nail (not shown) may be driven downwardly through the body portion 16 into one of the forward ribs 19 in a manner shown for the nail 15 in Fig. 4. The ribs 19 have a tendency to flatten out causing the lip 18 to become firmly engaged with the nap of a rug similarly shown in Fig. 4.

Fig. 6 is similar to Fig. 5 but showing a rug guard provided with a main body portion 20 having a tapered tail 17 and a tapered rug engaging lip 18 with the central section of the body portion 20 hollowed out as shown at 21. A nail not shown may be driven through the body portion 20 wherever convenient in order to secure the guard to the floor not shown.

Fig. 7 is a further modification of Fig. 6 showing a rug guard having a body portion 22 provided with a tapered tail 17 and a tapered and curved lip 18 with the central section of the body portion 22 provided with separate hollowed sections 23. A nail may be driven through the body portion 22 wherever convenient in securing the guard to the floor not shown.

Fig. 8 shows a rug guard having a solid body portion 24 provided with a tapered tail 17 and a tapered curved lip 18. The upper surface of the guard is provided with raised portions 25 extending the length of the guard and acting to prevent slipping thereon. The body 24 is also provided with a metal insert 26 which extends the length of the guard. This insert equalizes the pressure exerted by the screw 27 after it has been driven into guard holding position.

Fig. 9 shows another form of rug guard having a body portion 28 provided with a tapered tail portion 17 and a tapered and curved lip 18. The floor engaging bottom portion 29 is provided with a recessed slot 30 extending the length of the guard and forming a leg 31 which tends to shorten and permit the lip 18 to move into gripping position with a rug when the nail 32 is driven into holding position.

Fig. 10 shows a rug guard with a concave floor engaging base 33 which tends to grip the floor by suction created when the guard is pressed downwardly against the floor. To insure the guard holding fast a nail may be driven through the guard in the manner shown for Fig. 9. The concave form of the base also insures a positive contact of the tail portion 17 of the guard with the floor thereby forming a seal against the entrance of dirt under the leading edge of the guard.

Fig. 11 shows a rug guard having a body portion 34 provided with a tapered tail portion 17 and a rug engaging lip 18. The guard is further provided with an inverted wedge shaped slot 35 extending the length of the guard and adapted to receive the head 36 of the nail 37 in concealed and protected position. In this manner the nail 37 is protected against wear, and corrosive influences and also adds to the appearance of the guard in its rug holding position.

Each of the forms of rug guards described is made by extruding a rubbery material out of a die of the proper design. Any resilient rubbery material may be used. Natural and synthetic rubbers are preferred. Elastic synthetic resins

may be used as well as the plasticized resins including the acrylates, polyamides, vinyl chloride polymers and copolymers and the like.

While certain representative embodiments and details have been shown for the purpose of illustrating the invention, it will be apparent to those skilled in this art that various changes and modifications may be made without departing from the spirit or scope of the invention.

What is claimed is:

1. A device for holding a floor covering and the like against movement out of its normal position of lay on a support, the device comprising a resilient body portion and anchor means extending outwardly from said body portion, a resilient lip extending outwardly from said body portion and over said anchor means, securing means extending through said anchor means adjacent said lip and causing said lip to press said floor covering directly against said support when said device is secured by said securing means against the edge of said floor covering, said lip adapted to be moved upwardly out of biasing position with said covering whereby said covering can be freely removed from said device, and a tail portion starting from said body portion and tapering downwardly away therefrom in a direction opposite to the resilient lip for engagement with said support, whereby an approach to said covering is made over a surface formed by said device which rises gradually from the surface of said support to a plane substantially parallel with the upper surface of said covering.

2. A device for holding a floor covering and the like against movement out of its normal position of lay on a support, the device comprising a resilient body portion, an anchor means extending outwardly from said body portion, a resilient lip extending outwardly from said body portion and over said anchor means and adapted to be moved upwardly out of its normal biasing position to expose said anchor means and permit the insertion of securing means into said anchor means whereby said lip is forced into biasing relation with said floor covering thereby pressing said floor covering directly against said support and a tail portion starting from said body portion and tapering downwardly away therefrom in a direction opposite to the resilient lip for engagement with said support, whereby an approach to said covering is made over a surface formed by said device which rises gradually from the surface of said support to a plane substantially parallel with the upper surface of said covering.

SAMUEL P. JUNE.
